FIG. 2

INVENTOR.
PAUL HUDDLES

BY *Sol Shepperson*

ATTORNEY

UNITED STATES PATENT OFFICE

169,441

HEAD RAIL CHANNEL SECTION

Paul Huddles, Baltimore, Md., assignor to Globe Venetian Blind Corporation, Baltimore, Md., a corporation of Maryland

Application April 9, 1952, Serial No. 19,258

Term of patent 14 years

(Cl. D21—6)

To all whom it may concern:

Be it known that I, Paul Huddles, a citizen of the United States and resident of Baltimore, State of Maryland, have invented a new, original, and ornamental Design for a Head Rail Channel Section, of which the following is a specification, reference being had to the accompanying drawing, forming a part hereof.

Fig. 1 is a perspective view of a head rail channel section, showing my new design; and

Fig. 2 is a transverse cross-sectional view thereof.

I claim:

The ornamental design for a head rail channel section, as shown.

PAUL HUDDLES.
